UNITED STATES PATENT OFFICE.

CHARLES H. BOECK, OF JACKSON, MICHIGAN, ASSIGNOR TO THE NOVELTY MANUFACTURING COMPANY, OF SAME PLACE.

BLUE-FLAME OIL-STOVE.

SPECIFICATION forming part of Letters Patent No. 603,124, dated April 26, 1898.

Original application filed August 10, 1896, Serial No. 602,368. Divided and this application filed March 23, 1898. Serial No. 674,908. (No model.)

To all whom it may concern:

Be it known that I, CHARLES H. BOECK, a citizen of the United States, residing at Jackson, in the county of Jackson and State of Michigan, have invented certain new and useful Improvements in Blue-Flame Oil-Stoves; and I do hereby declare the following to be a full, clear, and exact description of the invention, such as will enable others skilled in the art to which it appertains to make and use the same.

My invention relates to improvements in oil-stoves or stoves which burn a liquid hydrocarbon, and more particularly to improvements in that class of stoves known as "blue-flame" oil-stoves, and the present application is a division of that filed August 10, 1896, Serial No. 602,368, in which is claimed the central draft-tube serving to both lift the commingling-chamber and to supply air to the flame of the burner.

The principal object of the invention is to evolve a more intense and effective heating-flame from a given supply of liquid hydrocarbon fuel than is possible in constructions heretofore in vogue, while at the same time preserving a simplicity and compactness in form such as calculated to improve the appearance and lend to the durability of the stove.

Other objects are to provide for keeping the burner cool by means of fresh-air currents induced in combustion and to provide improved means for conveniently manipulating the stove, including provision for obviating the giving off of offensive odors when the flame has been extinguished.

With the above-stated objects in view the invention consists in certain novel features of construction and combinations of parts recited in the appended claims, and preferred forms of which are specifically described hereinafter and illustrated in the accompanying drawings, whereof—

Figure 1 is a front elevation of an oil-stove embodying my invention, the side of the lower portion of the wick-tube being broken out and the wick-raising spindle being in cross-section. Fig. 2 is a sectional view on line II of Fig. 1, looking down. Fig. 3 is a verti-

cal sectional view on line III III of Fig. 1, and Fig. 4 is a top plan view of the burner portion and surrounding casing.

In the drawings similar letters of reference are employed to designate similar parts throughout the several views.

The reference-letter A designates the framework which supports the entire stove and upon which the top plate A' is fastened, said top plate having a suitable grate. A platform A" at the bottom part of the frame directly supports the burner and has an opening at the center to afford a central draft for the latter, and an oil-tank F is supported at a suitable elevation at the back side of the frame and communicates with the wick-section of the burner by a suitable pipe in the usual way. This wick-section is made up of concentric tubes C C', with the usual wick-lifter band w therebetween, which is operated by turning the handle or thumb-piece H' of a spindle H, the latter carrying a pinion w', in mesh with a pendent rack w" on the lifter-band. This spindle is preferably provided with an adjustable arm I, which strikes a suitable pin I', fixed to the outer casing of the burner and limiting movement of the wick up or down, and said adjustable arm preferably consists of a strip or band of sheet metal folded over the spindle and clamped thereto by a small screw-headed bolt. The outer tube C of the wick-section extends downwardly beyond the inner tube and is secured to the bottom plate or platform A", fitting over a suitable flange thereon, to which it is secured by any suitable means, and the inner tube C' is flanged at its lower end to close the wick-space, a suitable extension being provided to inclose the lifter-rack. At their upper ends the tubes C and C' are flanged outwardly and inwardly, respectively, and also upwardly to form an annular space on both sides of the protruding upper end of the wick, this being a common construction in this class of oil-stoves.

Secured to the outer tube C by suitable wings r is a cylindrical casing B, open at the top and bottom, and resting upon a suitable flange at the upper part of this casing B is a removable casing B', having a series of aper-

tures *a*, controlled by a suitable ring damper *B*', which may be manipulated by a knob *n* for closing said apertures to permit a circulation of air in the space between the burner and this outer casing or for opening said apertures to admit a current of air from the outside of said outer casing to check and partially prevent such circulation and to diffuse and oxidize the offensive gases arising from the burner when extinguished, said apertures being arranged just above the upper ends of the wick-tubes *C C'*. These apertures also permit the introduction of a match to light the wick when the mixing-chamber is raised. This mixing-chamber is made up of an outer perforated tube *E* and an inner perforated tube *E'*, the latter being secured directly to a central draft-tube *D* by rings *E'' E''*, providing an annular space or chamber *X*', adapted to supply heated air to the mixing-chamber. The outer tube *E* has an inwardly curved flange *e* at the top above the inner perforated tube *E'*, and the top row of perforations *e'* of this tube *E* are larger than those lower down to admit air more freely to complete combustion at this point. The mixing-chamber tubes are fixedly secured together by bolts and sleeves *i* and rest on the horizontal flanges at the top of the tubes *C* and *C'*, just inside the vertical flanges thereof, when the burner is in operation.

A tube *C''*, centrally located within and connected by suitable wings *t* to the inside of wick-tube *C'*, serves as a guide to properly locate the mixing-chamber above by reason of its embracing the central draft-tube *D*, which, together with the mixing-chamber, is vertically movable. From the lower end of this draft-tube *D* depends a rigid loop *G*, bearing upon a lever *G'*, which is pivoted to one side of the tube *C* and extends across the same and through a vertical slot *g* in the opposite side of the tube *C*, said slot having a notch *g'* in one side at the top. It will be seen that by raising and lowering the lever *G'*, as indicated by the dotted lines in Fig. 1, the draft-tube *D* and whatever is attached to the same will be raised, and when the lever is lowered the draft-tube and its attachments will return to their normal position by their own weight.

A cap *D'* is applied to the top of the draft-tube *D* and has a row of perforations *d* just above the latter to deliver air outwardly and produce a complete combustion of all vapors generated in the chamber below at a point directly beneath any vessel or object placed upon the grate. The cap *D'* can be made integral with the draft-tube *D*, but is preferably made separable to afford a convenient means of access for brushing and cleaning purposes. The draft-tube *D* is provided with a series of openings or perforations *d²* just beneath the lower ring *E''* to permit a free passage of cold air next to the inside of the wick-tube and is also perforated just above the said bottom ring *E''*, as shown at *d''*, and again higher up, as shown at *d'''*, to permit

free access of air to feed the heating-chamber *X* between inside tube *E'* of the generating and mixing chamber and the draft-tube, and another series of perforations or openings *d³* is provided just below the top ring *E'''* to insure a free circulation of air next to the inner side of the inner tube *E'*.

Having thus described the various parts of my improved blue-flame oil-stove and indicated their shape and relative position, I will now describe its operation and the method of using the same.

The tank *F* being filled with kerosene-oil, the wick *W* is raised to the proper point for ignition, and then by means of lever *G'* the draft-tube and the attached generating and mixing chamber are lifted and retained in the elevated position by moving the lever into the notch *e'*. Then the damper *B*' is opened and the wick lighted through one of the apertures *a*, a very small flame being used, and thereafter this damper is closed and the flame immediately heats the tubes *E E'* and the chamber intervening between the same and the draft-tube and induces a circulation which draws in air through the perforations, mixing the same thoroughly with the vapor and flame which travels upward toward the top. When the tubes *E E'* become thoroughly heated, a circulation of air takes place up through the bottom of the drum *B*, around the outside of the outer tube *E*, and supplies the flame with oxygen for inducing and supporting the combustion. A circulation also takes place up through the draft-tube *D*, which feeds the chamber *X* between it and the inner tube *E'*, causing a perfect mixing of heated air with the vapors rising from the wick. Air also circulates up around the outside of the tube *C''* and into the draft-tube *D* just beneath the bottom ring *E''*, and thus a supply of cold air is kept on the inside as well as on the outside of the wick-tubes. When the mixed vapor and air reaches the top, jets of fresh air enter the large perforations in the top of the tube *E* and rapidly increase the combustion at that point, and jets of fresh air spread outwardly from the cap *D'* and the inflammable gases are abundantly fed with fresh oxygen both from the inside and outside, causing a complete and fierce combustion to take place at the top of the tubes directly underneath any vessel or article placed on the grate above, which is the exact point where such combustion is desired. When the flame is extinguished, the damper *B*' should be immediately opened to check the draft past the tube, as heretofore explained, which is a prime cause in inducing foul odors from stoves of this class.

Having thus described my improved blue-flame oil-stove, I desire to state that it can be considerably varied in its details without departing from my invention. Other means might be provided for raising the draft-tube and its connected parts, though what I have shown for the purpose possesses great merit on

account of its great simplicity. A different style of drum B B' might be employed, though this structure of drum B is believed to be the simplest obtainable which will answer the purpose. The manner of connecting the tubes E E' is not material, and other means could be provided for attaching them to the central draft-tube. The outer tube E is very effective without the inwardly-projecting flange at the top, though this inwardly-projecting flange has the effect of concentrating the force of the flame and prevents a scattering of its heat. Other variations will no doubt suggest themselves to those skilled in the art to which my invention appertains. Therefore in the claims which follow I have recited what I consider the essential elements of the invention without restriction to specific structure.

Having thus fully described my invention, what I claim as new, and desire to secure by Letters Patent of the United States, is—

1. In an oil-stove, the combination with a wick-section, of a mixing-chamber arranged over the same, an inclosed annular air-chamber adjacent to said mixing-chamber and communicating therewith by suitable passages for supplying heated air thereto, and means for supplying fresh air to said inclosed air-heating chamber, substantially as described.

2. In an oil-stove, the combination with a wick-section, of a mixing-chamber arranged over the same, and an internally-arranged draft-tube separated from the mixing-chamber by a suitable air-space and provided with a suitable passage or passages for supplying air to the air-space, substantially as described.

3. In an oil-stove, a central-draft wick-section, an annular mixing-chamber arranged over the same, and a draft-tube arranged centrally within the mixing-chamber and separated therefrom by an annular space or chamber adapted to supply heated air to said mixing-chamber, said draft-tube being provided with suitable openings or passages adjacent to the lower portion of the mixing-chamber for supplying air to the annular air-space, substantially as described.

4. In an oil-stove, the combination with a central-draft wick-section, of a mixing-chamber suitably supported over the same, and a draft-tube arranged within the mixing-chamber and separated therefrom by a suitable space adapted to supply heated air thereto, said draft-tube being provided with a suitable passage or passages for supplying air from the interior of the burner to said air-space, and with an opening or openings at its upper portion for supplying air to the flame issuing from the mixing-chamber, substantially as described.

5. In an oil-stove, a central-draft wick-section, a mixing-chamber arranged over the same comprising concentric tubes provided with passages for air, and an inner draft-tube

separated from the mixing-chamber by an air space or chamber closed at both ends and provided with passages for supplying air to said air-space, substantially as described.

6. In an oil-stove, the combination with a central-draft wick-section, of a mixing-chamber arranged over the same, an inner draft-tube separated from said mixing-chamber by a suitable air-space and provided with passages for supplying air to said space from the interior of the wick-section, and a cap fitting the upper end of the draft-tube and provided with a suitable passage or passages to direct air into the flame issuing from the mixing-chamber, substantially as described.

7. In an oil-stove, the combination with a central-draft wick-section, of a mixing-chamber comprising concentric perforated tubes arranged over said wick-section, a central draft-tube, an annular space or chamber between the inner surface of the inner tube of the mixing-chamber and the draft-tube, and rings connecting said draft-tube to the mixing-chamber so as to close the ends of said air-space, said draft-tube being provided with air-passages for supplying air to the annular space or chamber, substantially as described.

8. In an oil-stove, the combination with a central-draft wick-section, of a mixing-chamber, comprising concentric perforated tubes arranged over said wick-section, a central draft-tube separated by annular spaces or chambers from the wick-section and the mixing-chamber and provided with passages or openings communicating with said spaces so as to create a circulation within the wick-section and to supply air to the annular space between the mixing-chamber and draft-tube, together with means for causing a draft around the outer surface of the wick-section, whereby cold air may be caused to circulate both around the inner and outer surfaces of said wick-section to keep the latter cool, substantially as described.

9. In an oil-stove, the combination with a central-draft wick-section, of a mixing-chamber arranged over the same, a central draft-tube and connections therewith for supplying air from the interior of the wick-section to the mixing-chamber, together with an open-ended outer casing for causing a draft or circulation of air around the outer surface of the wick-section to keep the latter cool, substantially as described.

10. In an oil-stove, the combination with a central-draft wick-section, of a mixing-chamber provided with air-passages arranged over said wick-section, and an inner draft-tube separated from the mixing-chamber by an air space or chamber closed at its ends and from the wick-section by a chamber or air-space having its lower end open and its upper end closed, said draft-tube being provided with a passage or passages communicating with the air space or chamber between the mixing-chamber and the draft-tube and with a passage or passages communicating

with the upper portion of the chamber or space between said tube and the wick-section, whereby air may be caused to circulate against the inner surface of the wick-section and air supplied to the space between the draft-tube and mixing-chamber, substantially as described.

11. In an oil-stove, the combination with a central-draft wick-section, of a mixing-chamber comprising concentric tubes arranged over said wick-sections, together with a central draft-tube separated from the mixing-chamber by an air space or chamber and provided with suitable passages for supplying air to said space from the interior of the wick-section, said outer tube of the mixing-chamber being taller than the inner tube and having its upper end flanged or turned inwardly to concentrate the heat, substantially as described.

12. In an oil-stove, the combination with a suitable wick-section, of a mixing-chamber arranged over the same, an inner draft-tube separated from the mixing-chamber by a suitable air space or chamber and provided with passages for supplying air to said space, said draft-tube being attached to the mixing-chamber so as to move vertically therewith, together with means for raising said draft-tube and mixing-chamber to permit the wick to be lighted, substantially as described.

13. In an oil-stove, the combination with a central-draft wick-section, of a mixing-cham-

ber arranged over the same, an outer casing having an opening or openings at the height of the wick-section, and a ring-damper for controlling said opening or openings, substantially as described.

14. In a blue-flame oil-stove, the combination of an annular wick-tube, a vertically-movable commingling-chamber situated thereabove, and a lifting and air-feeding tube extending within the commingling-chamber and forming between the latter and itself an air-heating chamber in communication with the commingling-chamber, said tube communicating with said air-heating chamber and depending within the wick-tube.

15. In a blue-flame oil-stove, the combination of an annular wick-tube, a vertically-movable commingling-chamber situated thereabove, and a lifting and air-feeding tube extending within the commingling-chamber and forming between itself and the latter an air-heating chamber in communication with the commingling-chamber, said tube communicating with said air-heating chamber and feeding air to the principal flame of the burner, substantially as described.

In testimony whereof I affix my signature in presence of two witnesses.

CHARLES H. BOECK.
